UNITED STATES PATENT OFFICE

163,540

BICYCLE HANDLEBAR STEM OR SIMILAR ARTICLE

Charles H. Parton, Ossining, N. Y., assignor to
D. P. Harris Hardware & Manufacturing Co.,
Inc., New York, N. Y.

Application December 29, 1948, Serial No. 150,426

Term of patent 14 years

(Cl. D90—11)

To all whom it may concern:

Be it known that I, Charles H. Parton, a citizen of the United States of America, residing at Ossining, county of Westchester, and State of New York, have invented a new, original, and ornamental Design for a Bicycle Handlebar Stem or Similar Article, of which the following is a specification, reference being had to the accompanying drawing, forming a part thereof.

Fig. 1 is a perspective view of a bicycle handlebar stem, showing my new design; and

Fig. 2 is a front elevational view thereof.

I claim:

The ornamental design for a bicycle handlebar stem or similar article, as shown.

CHARLES H. PARTON.
